ATTORNEY

UNITED STATES PATENT OFFICE.

ROBERT E. JELLISON, OF NEW AUBURN, MINNESOTA.

CONNECTER.

Application filed June 4, 1924, Serial No. 717,911. Renewed July 1, 1925.

To all whom it may concern:

Be it known that I, ROBERT E. JELLISON, a citizen of the United States, residing at New Auburn, in the county of Sibley and 5 State of Minnesota, have invented new and useful Improvements in Connecters, of which the following is a specification.

The object of my said invention is the provision of a connector susceptible of use to 10 advantage in many relations and characterized by a capacity to be released while fully loaded or subjected to strong pull and also characterized by the capacity of resisting release until it is operated in the manner to 15 be described by an operator.

Other objects and practical advantages of the invention will be fully understood from the following description and claims when the same are read in connection with the 20 drawings, accompanying and forming a part of this specification, in which:

Figure 1 is a detail side elevation of one of the side sections of the connector.

Figure 2 is an edge elevation of a connector constructed in accordance with my 25 invention.

Figure 3 is a vertical section showing the connector as closed.

Figure 4 is a similar view showing the 30 connector as open.

Figure 5 is a longitudinal central section taken in the plane indicated by the line 5—5 of Figure 4.

Figure 6 is top plan view of the connector.

Figures 7, 8, 9 and 10 are perspectives of elements comprised in the connector and hereinafter referred to in detail.

Similar numerals of reference designate 40 corresponding parts in all of the views of the drawings.

Among other elements my novel connector comprises an aperture housing, the housing in the embodiment illustrated including side 45 sections 1 and 2, appropriately held together as by bolts 3 and nuts 4 and also including edge sections 5 and 6 in the latter of which is an opening 7. It will also be noticed that the side sections 1 and 2 are provided in 50 their inner sides with recesses 8 of general angular configuration as appears in Figures 1 to 3. I would also have it understood that when desired the housing section 2 may be provided with a bracket 9 for the pivotal 55 connection of a bail 10 in which is mounted an anti-friction roller 11, adapted to be dis-

posed in the loop of a piece of harness or the like.

Disposed and movable in the angular recesses 8 are the end portions 12 of a transverse member, Figures 5 and 7; the said transverse member also comprising an intermediate portion 13 having reduced ends 14 of angular form in cross-section.

Mounted on the said portions 14 of the 60 transverse member are links 15 having angular apertures 16 and 17, and connected together by a transverse pin 18.

Pivottally mounted on opposite bolts 3 are the jaws 19 and 20 of my improvement, 70 the bolts referred to being arranged at opposite sides of the inner ends of bifurcations 21' in the housing sections 1 and 2, and the jaws being adapted to be moved from the positions shown in Figure 3 to the positions 75 shown in Figure 4 and vice versa. The jaws 19 and 20 are preferably shaped as shown though they may be otherwise shaped in consonance with my invention without involving departure from the scope of the 80 invention as claimed.

Fixed to the jaw 19 is an arm 21 relatively arranged as illustrated, and interposed between and connected to said arm 21 and the before mentioned transverse pin 18 is a 85 retractile spring 22. The inner portions of the jaws 19 and 20 are provided with apertures 23 in their inner portions, the said apertures 23 being of circular form to receive the circular portion 24 of a second 90 transverse member, Figure 8, which transverse member in addition to the circular portion 24 is provided with angular end portions 25 which are disposed in the angular apertures 17 of the links 15.

Connected to the first-named transverse member of the device, which member for identification is generally numbered 30, is a cable section 31 which extends through and is movable in the opening 7 and is designed to be used by an operator in opening the connector—i. e., moving the jaws 19 and 20 and their appurtenances from the positions shown in Figure 3 to the positions shown in Figure 4. When pull is exerted on the cable 31 in a direction away from the housing, the jaws 19 and 20 will be opened, the spring 22 will be expanded, and the member 30 will be moved in the recesses 8. Consequently, the spring 22 will be 105 enabled to yieldingly retain the jaws 19 and 20 in the open positions. When, however,

any device 32 such as a link of a chain or ring thereof to be engaged by the connector is thrust in the direction indicated by arrow in Figure 4 against the connected portions 5 of the jaws, the jaws and the links 15 will be moved in the direction of the arrow until the transverse member 30 reaches the upper arms of the recesses 8 whereupon the spring 22 will promptly contract and close the jaws 10 upon the said device 32 which obviously may be of any description.

By reference to Figure 3 in which device 32 is shown by way of example, it will be manifest that when the jaws are snapped 15 closed, the device 32 will be confined in the jaws, and any pull exerted on the device 32 in the direction opposite to that indicated by arrow in Figure 4 will only serve to more strongly hold the jaws in closed state, with 20 the result that there is no liability whatever of a device held in the connector being casually released.

It will be apparent from the foregoing that my novel connector may be employed to 25 advantage in very many relations, and it will also be apparent that the connector is compact and strong in construction and is therefore well adapted to withstand rough usage to which connectors are ordinarily 30 subjected in heavy work.

I have specifically described the preferred embodiment of my invention in order to 35 impart a full, clear and exact understanding of the said embodiment. I do not desire, however, to be understood as confining myself to the specific construction and relative arrangement of elements as described inasmuch as in the practice of my invention 40 various changes may be made within the scope of my appended claims which define my invention.

Having described my invention, what I 45 claim and desire to secure by Letters-Patent, is:—

1. A connector comprising a housing, swinging jaws in and connected to said housing, swinging means in the housing and connected to the jaws and movable endwise coincident to the opening and closing of the 50 jaws, a retractile spring interposed between and connected to said swinging means and one of the jaws, and co-operating means carried by the housing and swinging means for yieldingly retaining the jaws in open 55 positions when the said spring is tensioned.

2. A connector comprising a housing, swinging jaws in and connected to said

housing, swinging means in the housing and connected to the jaws and movable endwise coincident to the opening and closing of the jaws, a retractile spring interposed between and connected to said swinging means and one of the jaws, and co-operating means carried by the housing and swinging means for yieldingly retaining the jaws in open 60 positions when the said spring is tensioned; the housing being provided with an opening, and a cable being extended through said opening and connected with said swinging and endwise movable means. 65

3. A connector comprising a housing having opposite sections and angular recesses in the inner sides of said sections, swinging jaws in and connected to the housing, swinging and endwise movable means connected to the jaws and having a transverse member with ends disposed and movable in said recesses, and a retractile spring interposed between one of the jaws and the said swinging 70 portions. 75

4. A connector comprising a housing having sections with bifurcated ends and with angular recesses in their inner sides, swinging jaws pivoted in the housing at opposite sides of the inner ends of said bifurcations, one of the jaws having an inwardly extending arm, links connected to the inner arms of the jaws and arranged to swing and move endwise, a retractile spring connecting said links and the arm on one jaw, and a transverse member interposed between and connected to said links and having end portions disposed and movable in said angular recesses of the housing sections. 80

5. A connector comprising a housing having opposite sections with end bifurcations, arms with angular recesses in their inner sides, jaws pivoted in said housing at opposite sides of the inner portions of said bifurcation, one of the jaws having an arm, a transverse member extending through and pivoted in lapped portions of the jaws and having angular apertures receiving the angular ends of said transverse member, and a second transverse member having ends movable in said angular recesses and also having portions of angular cross-section disposed in angular apertures of the links, and a retractile spring interposed between and connected to the arm on one jaw and the said links. 90 95 100 105 110

In testimony whereof I affix my signature.

ROBERT E. JELLISON.
